(21) Appl. No.: **29/274,000**

(57) **CLAIM**

(22) Filed: **Mar. 19, 2007**

I claim the ornamental design of a helicopter blade-section display plaque, as shown and described.

(51) **LOC (8) Cl. 11-02**

DESCRIPTION

(52) **U.S. Cl. D11/132**

FIG. 1 is a front view of a helicopter blade-section display plaque of the present invention.

(58) **Field of Classification Search D11/131-142, D11/157-164, 184; 416/226, 42; 156/228**

FIG. 2 is a right side elevational view of the helicopter blade-section display plaque of FIG. 1.

See application file for complete search history.

FIG. 3 is a top plan view of the helicopter blade-section display plaque of FIG. 1.

(56) **References Cited**

FIG. 4 is a bottom plan view of the helicopter blade-section display plaque of FIG. 1.
